US00D703719S

(12) **United States Design Patent**
Boyle et al.

(10) **Patent No.:** **US D703,719 S**
(45) **Date of Patent:** **** Apr. 29, 2014**

(54) **ELECTRONIC COMMUNICATION DEVICE**

(75) Inventors: **Christopher T. Boyle**, San Antonio, TX (US); **Scott Taylor**, San Antonio, TX (US); **Alexander G. Sammons**, San Antonio, TX (US); **John T. O'Callaghan**, San Antonio, TX (US); **Christian Elder**, Baltimore, MD (US)

(73) Assignee: **H4 Engineering, Inc.**, San Antonio, TX (US)

(**) Term: **14 Years**

(21) Appl. No.: **29/414,910**

(22) Filed: **Mar. 5, 2012**

(51) **LOC (10) Cl.** **16-05**

(52) **U.S. Cl.**

USPC **D16/237**

CLAIM

The ornamental design for an electronic communication device, as shown and described.

DESCRIPTION

FIG. 1 is an isometric perspective view of our design;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines in the drawings depict features that form no part of the claimed design.
